United States Patent Office

Des. 192,927
Patented May 29, 1962

192,927

COMBINED FINGER, WRIST AND FOREARM EXERCISER

Charles F. Ernst, 1629 Polk St., San Diego, Calif.

Filed Sept. 1, 1961, Ser. No. 66,582

Term of patent 14 years

(Cl. D34—5)

FIG. 1

FIG. 2

FIG. 1 is a plan view of a combined finger, wrist and forearm exerciser showing my new design; the other side being substantially the same; and

FIG. 2 is a side elevation thereof.

I claim:

The ornamental design for a combined finger, wrist and forearm exerciser, as shown and described.
